[57] CLAIM

The ornamental design for a nachos vending unit, as shown and described.

DESCRIPTION

FIG. 1 is a right side elevational view of a Nachos Vending Unit showing my new design;

FIG. 2 is a left side elevational view thereof;

FIG. 3 is a top plan view thereof;

FIG. 4 is a bottom plan view thereof;

FIG. 5 is a front elevational view thereof;

FIG. 6 is a top, rear, right side perspective view thereof;

FIG. 7 is a top, rear, right side perspective view thereof with one lid in an open position.
The view, not shown, of the other hinged lid in a partly raised position, is similar to the view shown in FIG. 7, except that the interior is plain and unornamental.
